WILLIAM WILLHEIM, OF NEW YORK, N. Y.

DESIGN FOR A TEXTILE FABRIC COLLAR OR SIMILAR ARTICLE

Application filed December 1, 1932. Serial No. 46,242. Term of patent 3½ years.

To all whom it may concern:

Be it known that I, WILLIAM WILLHEIM, a citizen of the United States of America, residing at 115 Central Park West, in the city of New York, county of New York, and State of New York, have invented a new, original, and ornamental Design for a Textile Fabric Collar or Similar Article, of which the following is a specification, reference being had to the accompanying drawing, forming a part thereof.

The figure is a plan view of a textile fabric collar showing my new design. For conven-

ience of illustration and to show the design more in detail the same has been divided. The design is continuous. The dot and dash lines AB and A¹B¹ respectively coincide and overlie each other. The drawing is lined to indicate shading.

I claim:

The ornamental design for a textile fabric collar or similar article as shown and described.

In testimony whereof I have signed this specification.

WILLIAM WILLHEIM.
